203,669

AUTOMOBILE ORNAMENT

Melvin G. Carpenter, 1178 Broadway,
Benton Harbor, Mich.

Filed Apr. 30, 1965, Ser. No. 85,044

Term of patent 3½ years

(Cl. D14—18)

FIG. 1 is a side elevational view of an automobile ornament showing my new design;

FIG. 2 is a front elevational view of the automobile ornament of my new design;

FIG. 3 is a front perspective view of the automobile ornament showing my new design;

FIG. 4 is a transverse sectional view taken on line 4—4 of FIG. 1;

FIG. 5 is a transverse sectional view taken on line 5—5 of FIG. 1.

The side of the automobile ornament opposite that shown in FIG. 1 is of the same appearance as shown in FIG. 1.

I claim:

The ornamental design for an automobile ornament, as shown.
